CLAIM

The ornamental design for a visor for telescopic lifter, as shown and described.

DESCRIPTION

FIG. 1 is a back-left side-top perspective view of a visor for telescopic lifter, showing the new design;

FIG. 2 is a left side view thereof, the right side view being a mirror image thereof; and,

FIG. 3 is a top view thereof.

The broken lines in the drawings illustrate unclaimed environmental structure and form no part of the claimed design.
